(57) **CLAIM**

The ornamental design for a sweeper having a plastic blade for sweeping water and dust, as shown and described.

DESCRIPTION

FIG. 1 is a perspective view of my new design showing a sweeper having a plastic blade for sweeping water and dust; FIG. 2 is a magnified view of part 2 in FIG. 1

FIG. 3 is a side elevation view thereof, the other side being a mirror image; and,

FIG. 4 is a magnified view of part 4 in FIG. 3 front elevational view thereof.

The broken line showing of environment is for illustrative purposes only and forms no part of the claimed design.
